(57) **CLAIM**

We claim the ornamental design for an implantable venous device, as shown and described.

DESCRIPTION

FIG. 1 is a perspective view of an implantable venous device showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof; FIGS. 1-3, 6 and 7 show the tube member in fragment to indicate indeterminate length.

FIG. 1-3, 6 and 7 show the tube member in fragment to indicate indeterminate length.
